US0D1073750S

(12) **United States Design Patent** (10) **Patent No.:** **US D1,073,750 S**
(45) **Date of Patent:** **** May 6, 2025**

(54) **MANUAL PRESS MACHINE**

(71) Applicant: **Shenzhen Yisheng Technology Co., Ltd.**, Guangdong (CN)

(72) Inventor: **Caiying Yang**, Guangdong (CN)

(73) Assignee: **Shenzhen Yisheng Technology Co., Ltd.**, Shenzhen (CN)

(**) Term: **15 Years**

(21) Appl. No.: **29/926,031**

(22) Filed: **Jan. 29, 2024**

(30) **Foreign Application Priority Data**

Dec. 28, 2023 (CN) 202330861820.X

(51) **LOC (15) Cl.** **15-09**

(52) **U.S. Cl.**
USPC **D15/123**

(58) **Field of Classification Search**

(57) **CLAIM**

The ornamental design for a manual press machine as shown and described.

DESCRIPTION

FIG. 1 is a front elevational view of a manual press machine showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, rear and left side perspective view thereof;

FIG. 8 is a top, front and right side perspective view thereof;

FIG. 9 is a bottom, front and right side perspective view thereof; and,

FIG. 10 is a top, rear and left side perspective view showing the manual press machine in a state of use.

The broken lines in the drawings illustrate portions of the manual press machine which form no part of the claimed design.

1 Claim, 10 Drawing Sheets
